Attorney:

UNITED STATES PATENT OFFICE

JOHN ARTHUR PERRY, OF MAIDSTONE, VICTORIA, AUSTRALIA

CARBURETOR

Application filed June 6, 1928, Serial No. 283,279, and in Australia June 14, 1927.

This invention relates to carburetors fixed to and used in internal combustion engines, and its objects are to provide an improved carburetor in which the liquid fuel is thoroughly vaporized and filtered, before the gas formed by the admixture of liquid fuel and air is admitted to the cylinder or cylinders of the engine, and to maintain a standard quality of mixture or gas.

10 The invention is illustrated by the accompanying drawings, whereof,

Figure 1 is a longitudinal vertical section of a practical form of the invention.

15 Figures 2, 3 and 4 are plan views of baffle plates, shown in Figure 1.

Figure 5 is a plan of a choke.

According to these drawings the float chamber 1 is located adjacent a cylindrical casing 2 and preferably formed integral with 20 the same.

The liquid fuel passes from the float chamber down an outlet passage 3 formed in the bottom 4 of said chamber and opening into a well or trap 5 below its lower end, which 25 well is in communication with an inlet passage 6 formed in the bottom 7 of the casing 2, said inlet passage being upwardly inclined and communicating with the fuel jet or nozzle 8 in the casing.

30 By means of this construction any water in the fuel will drain from both passages 3 and 6 into said well 5. The latter is closed at the bottom by a hollow screw plug 9 in alignment with passage 3 and can be removed to 35 empty the well and permit the passage 3 being cleared of any foreign matter or obstruction.

For the purpose of facilitating the cleaning of passage 6 the wall of the well is formed 40 with a hole normally closed by a screw plug 10 in alignment with passage 6.

45 Adjacent the discharge end of the fuel jet 8 is an automatically adjustable choke 11 normally retained on a seating 12 formed in the wall of the casing 2 by a spring 13. Said choke is formed with a central annular upturned mouth 14 which is flared towards its lower or inlet end, and around said mouth is an annular well 15.

50 The upper discharge end of the fuel jet

is located within the mouth of the choke, and the air inlet 16 in the casing is below the discharge end of the jet and the choke.

It may be stated at this point, that the lifting of the choke 11 does not increase the 55 air supply area, but actually reduces the suction of the petrol supply; that is to say, the mixture is proportioned by the intensity of the suction. If the choke is lower, the amount of fuel drawn up will be greater than 60 when it is lifted, according as the area of the orifice in the choke is, or is not in close proximity to the jet, which is another way of saying that more air is admitted.

The purpose of the well 15 of the choke 65 is to collect non-vaporized liquid fuel, which eventually is vaporized and becomes admixed with the air.

The casing is provided above or in advance of the fuel jet and the choke, with a central 70 primary baffle 18 formed with radial lugs 33 (Fig. 4) supported on a seating 23 in the wall of the casing. Said baffle is located above or in advance of the annular lip 43 of the mouth of the choke and there is an 75 annular conical passage 19 around said baffle.

The baffle 18 is of conical shape with a rounded end 20 and is hollow, the interior wall surface being formed with a series of annular serrations or steps 21.

80 The effect of this baffle is that the admixture of fuel and air strikes the serrations which give the mixture a swirling action and bring the fuel and air into more intimate association and furthermore causes any non-vaporized fuel or liquid therein to drop into 85 the well 15.

Surrounding the inner baffle 18 is another or outer baffle 22 formed with radial lugs 34 (Fig. 3) which rest on lugs 33 and are secured by screws 34^a, said baffle 22 being of conical section, i. e., it tapers interiorly towards its mouth 24 and is formed with a series of annular serrations or steps 25, the edges of which are preferably parallel with those of the baffle 18. Around the mouth 24 is an annular well 44 that collects any non-vaporized fuel.

90 The combustion mixture or gas passing through the passage 19 between the inner 95 100

and outer baffles is again subjected to a swirling action which tends to improve said mixture further, as well as to remove non-vaporized liquid; and finally the mixture meets still a third baffle 26 arranged transversely of the casing at a distance from the mouth of baffle 22. This baffle 26 rests or abuts against the edge of the cylindrical casing 40 of baffle 22 and is formed with a ring 10 of outlets 27, while its central non-perforated portion 28 is located above or centrally, in advance of the mouth 24 of baffle 22, and is preferably made concave as at 29 on the underside, said baffle being the final one employed to ensure and maintain a standard quality of mixture or gas.

It will be understood that if there is any non-vaporized fuel still in the mixture it will strike the concave surface 29 of the central portion 28 and that any striking the serrations 25 of baffle 22 will drip into well 15 which is in alignment with the entrance of passage 19.

In advance of the baffle 26 within the casing is the usual butterfly or other valve 30 controlling the supply of the combustible mixture to the cylinder or cylinders of the engine.

The choke 11 may be guided in its movements by means of arms 31 connected to a collar 32 slideable on the jet 8.

According to the construction described the mixture of liquid fuel and air is drawn by suction through the automatic choke 11 and impinges against the serrated interior surface of the first or lower baffle 18 wherein its course is deflected tangentially toward the lower edge of said baffle. It is then drawn up through the second or intermediate baffle 22, the effect of the serrations 25 on the surface of that baffle being to impart a centrifugal motion to the gas or mixture which thereby precipitates any unvaporized fuel or other liquid into the well 15 and prevents it from passing to the induction pipe and cylinders.

The baffle 26 completes the admixture of the fuel and air which passes through valve 30 to the intake manifold of the engine.

It must be understood that the invention is also applicable to a carburetor disposed in a horizontal or inclined position.

I claim:

1. In a carburetor, a casing having an air inlet, a fuel jet therein, a hollow conical baffle located centrally of said casing and fuel jet and in advance of the latter, the interior wall of said baffle being formed with serrations, and another baffle of conical section located outside the first one and formed with a central mouth surrounding the same, with a passage between said baffles, the interior surface of the outer baffle being formed with serrations.

2. In a carburetor, a casing having an air inlet, a fuel jet therein, a hollow conical baffle

located centrally of said casing and fuel jet and in advance of the latter, the interior wall of said baffle being formed with serrations, and another baffle of conical section located outside the first one and formed with a central mouth surrounding the same, with a passage between said baffles, the interior surface of the outer baffle being formed with serrations, said outer baffle being provided around its mouth with a well.

3. In a carburetor for internal combustion engines, a casing having an air inlet, a fuel jet therein, a movable adjustable choke controlled by the engine suction and provided with an annular well, and inner and outer baffles, one within the other, with an annular conical passage between the same in alignment with the well of said choke.

4. In a carburetor for internal combustion engines, a casing having an air inlet, a fuel jet therein, a movable choke controlled by the engine suction and provided with an annular well, an inner conical hollow baffle above said choke, and an outer conical section baffle provided with a central mouth and with a well around said mouth, the outer baffle surrounding the inner baffle and spaced therefrom by an intermediate conical passage, each baffle being formed on its interior surfaces with a series of steps.

5. In a carburetor for internal combustion engines, a casing having an air inlet, a fuel jet therein, a movable adjustable choke controlled by the engine suction and provided with an annular well, an inner conical hollow baffle above said choke, an outer conical section baffle provided with a central mouth and with a well around said mouth, the outer baffle surrounding the inner baffle and spaced therefrom by an intermediate conical passage between the baffles, each baffle being formed on its interior surfaces with a series of steps, and a third baffle located transversely in the casing and formed with a ring 95 of outlets surrounding a central non-perforated portion formed on the underside with a concave surface.

In witness whereof I have signed this specification.

JOHN A. PERRY.
